BOTTLE LOADING CARTON

Hubert Velman Bolding, Jeffersonville, Ind., assignor to
The Bradley & Gilbert Company, Louisville, Ky., a
corporation of Kentucky

Application August 10, 1949, Serial No. 109,549

6 Claims. (Cl. 220—113)

This invention relates to cartons for bottles and has particular reference to a container providing individual cells and formed from a single blank of sheet material.

One important use contemplated for the carton is in connection with non-returnable beer bottles. The glass manufacturers are interested basically in a carton, the cost of which is reduced to the very minimum, in which they can pack such bottles at the factory and ship them to the breweries, the bottles being packed in the carton at the factory in inverted position. The breweries demand a container which can be inverted to dispose the bottles in operative relation to the filling machine with the least amount of handling. These same containers will then be used by the breweries to insert a predetermined number of filled bottles, thus making the entire unit a so-called "one-time" package.

The so-called non-returnable beer bottle is of thin glass and will break relatively easily, thus necessitating good sturdy partitions between each individual bottle. It is essential, to both the manufacturer and the brewery, that the container be one in which the bottle can be readily placed or extracted without risking collapse of the container when the bottles are removed. It is also of optimum importance to provide a container that is easily assembled, eliminating all need for any considerable labor in assembling and reducing the number of operations required to a minimum.

This invention seeks to provide all of the attributes above noted. Various other objects and advantages of the invention will be apparent from the following description taken in conjunction with the drawings, wherein like numerals refer to like parts throughout the several figures and wherein:

Fig. 1 is a plan view of the blank from which my improved carton is formed;

Fig. 2 is a similar view illustrating the first folding operation;

Fig. 3 is an elevation of Fig. 2;

Fig. 4 is a plan view illustrating the second folding operation;

Fig. 5 is a plan view illustrating the third folding operation;

Fig. 6 is an elevation of Fig. 4;

Fig. 7 is an elevation of Fig. 5;

Fig. 8 is a section through the assembled carton;

Fig. 9 is a perspective of the assembled carton;

Fig. 10 is a perspective showing the carton ready for use;

Fig. 10a is a transverse section of a loaded carton;

Fig. 11 is a plan view of a modified blank providing twelve cells;

Fig. 12 is a plan view illustrating the first folding operation in forming the modified construction;

Fig. 13 is an end view of Fig. 12;

Fig. 14 is a plan view illustrating the second folding operation;

Fig. 15 is an end view of Fig. 14;

Fig. 16 is a plan view after the third folding operation;

Fig. 17 is an end view of Fig. 16;

Fig. 18 is a section through the completely assembled carton;

Fig. 19 is a perspective illustrating the completely assembled carton ready to be set up for use;

Fig. 20 is a perspective of such carton set up for use, and

Fig. 21 is a section through Fig. 20.

Referring now to Fig. 1, which illustrates the single

2

integral blank of sheet material from which the preferred embodiment of the invention is developed, it will be noted that two identical transverse series of elements are embodied in the blank. Each of the elements in the upper transverse series which is not in all respects symmetrical is reflected in the lower transverse series in converse or mirror-reflected position. The blank comprises side wall panels 22 and 22', end wall panels 20, 20' and 24, 24', and partition-forming sections. One pair of the partition-forming sections has first longitudinal partition-forming panels 18 and 18' and cross partition-forming and side wall engaging panels 10, 12, 14, 16 and 10', 12', 14', 16'. The other pair of the partition-forming sections has second longitudinal partition-forming panels 26 and 26'. More specifically, the blank comprises locking tabs 10 and 10', partitions 12 and 12', side wall reinforcing sections 14 and 14', partitions 16 and 16', component side wall sections 18 and 18', end walls 20 and 20', side walls 22 and 22', end walls 24 and 24', and component side wall sections 26 and 26'. All of these elements or sections of the blank in each respective transverse series, such as 10-26 and 10'-26', are delineated by vertical score lines.

Only two of the upper and lower identical sections are connected to one another by score lines, side wall sections 18 and 18' and side wall sections 26 and 26' being connected to one another by score lines 28 and 30, respectively. All of the other elements or sections of the upper transverse series are completely separated from their respective mirror duplicates in the lower transverse series, the blank being completely die cut through transversely excepting only at the aforesaid juncture lines or score lines 28 and 30. The locking tabs 10 and 10' are adhesively surfaced as indicated at 32, as are the outer margins of side wall sections 26 and 26', this latter adhesive application being indicated by the numeral 34. The under faces, as viewed in Fig. 1, of side reinforcing sections 14 and 14' are adhesively surfaced, as most clearly indicated at 36 in Fig. 2.

In the modification here being described, a series of closure flaps 38, 40, 42, 44 and 46 are positioned along the upper margin of the blank, being separated by score lines from their adjacent container sections. A similar series 38'-46' are similarly disposed along the lower margin of the blank.

Referring now particularly to Figs. 2 and 3, wherein the initial forming operation is illustrated, the left end of the blank in Fig. 1 is folded along the score lines separating sections 14, 16 and 14', 16', thus bringing the adhesive surface 32 on tabs 10 and 10' into contact with side wall sections 18 and 18' and exposing the adhesively surfaced faces 36 of sections 14 and 14'.

In Fig. 4 the left-hand end of the blank as it appears in Figs. 2 and 3 has been folded along the score lines separating side wall sections 18, 18' and end walls 20, 20', thus bringing the adhesively surfaced faces 36 of sections 14, 14' into face-to-face contact with the central portion of side walls 22 and 22'. In the form illustrated the width of side reinforcing sections 14 and 14' is equal to one third of the width of side walls 22 and 22' and when the sections 14 and 14' are adhered to the side walls they will not only reinforce these particular side walls throughout their center area, but position adjacent partition sections 12, 12' and 16, 16'. The division spaces need not, however, be equal.

Fig. 5 illustrates the final folding operation wherein the right-hand end of the blank has been folded over along the score lines separating side walls 22, 22' from end walls 24, 24', thus bringing the glued surfaces 34 of side wall sections 26, 26' into face-to-face contact with a marginal portion of cooperating side wall sections 18, 18', which latter are overlapped by the adhesively surfaced marginal portions of sections 26 and 26'. The adhesively coated surfaces may be adhered after all three folding operations have been performed or, if preferred under certain circumstances, each may be adhered successively as the folding operations bring the coated surfaces into proper position.

After completing the operations outlined above in conjunction with the blank as illustrated in Figs. 1-7, the carton is fully assembled but in collapsed flat con-

dition as indicated in Figs. 5 and 7. Pressure exerted by squeezing opposite side margins of the collapsed carton as shown in Figs. 5 and 7 causes the carton to open into the form illustrated in Figs. 8 and 9, wherein the walls and partitions formed by both the upper and lower series of transverse sections hitherto described in conjunction with Fig. 1 are in absolute alignment, forming a series of three cells extending straight through the unit.

As has been noted heretofore in describing Fig. 1, the two transverse series of elements or sections are connected only by score lines 28 and 30 which, when component wall sections 18 and 26, 18' and 26' have been integrated to form composite side walls for the upper and lower sections broadly indicated by the numerals 56 and 52 in Fig. 9, constitute together a juncture line joining sections 50 and 52. This single line of joinder constitutes a hinge line 54 about which the sections can be swung to provide a double row of three cells as indicated in Fig. 10. It should be noted here that the carton in the form illustrated in Fig. 10 may be collapsed into substantially flat condition, as well as in the form illustrated in Fig. 9.

The notches 56 and 58 in the adhesively surfaced marginal portion of component side wall sections 26 and 26', when the carton is assembled, encompass the ends, respectively, of hand holds 60 and 62. These hand holds are die cut through component side wall sections 18 and 18', the die cut extending completely around the opening except for marginal portions indicated at 64 and 66, thus leaving flaps 68 and 70 which may be swung out of the plane of their respective openings to facilitate grasping the loaded carton. As will be apparent, the openings 60 and 62 forming the hand holds are disposed in registry with one another when sections 50 and 52 are swung over to the position indicated in Fig. 10. The flaps 68 and 70 may be swung outwardly and upwardly as indicated in Fig. 10a, or both may be swung in the same direction to reduce any tendency of the material at the edge of the opening to cut into the carrying fingers.

Preferably the carton in the particular use contemplated primarily herein (throw-away beer bottles) will be shipped to the glass manufacturer in the form illustrated in Figs. 5 and 7, flattened for facilitating shipment and storage. By simply using an ordinary carton sealing machine the glass manufacturer can easily and quickly fold and glue or adhere end closures 38-46 and 38'-46'. Then simply swinging the two sections about the hinge line renders the carton ready for use. The glass manufacturer preferably inserts the new and empty bottles into the carton as illustrated in Fig. 10 in inverted position, necks down. The loaded carton is then shipped to the brewer.

The brewer inverts the carton, depositing the empty bottles right side up on an endless conveyor leading to the filling machine, and sets the carton down on the conveyor adjacent the bottles or upon a parallel conveyor moving in the same direction. The bottles are filled at the next station, capped, and then inserted without loss of time or excess motion into the same empty carton, which has reached the proper station at the proper time. The loaded cartons are then removed from the conveyor and stacked for shipment.

From the above description it will be apparent that the partitions are rigidly adhered in their respective positions and will maintain these positions throughout the life of the carton. This not only provides stability to the contents but adds rigidity to the carton. The partitions run from the bottom to the top, offering complete protection. Furthermore, bottles may be inserted into the cells formed by the partitions with equal ease and protection, regardless of whether the bottoms of the bottles are up or down. By virtue of the rigidity inherent in the construction, the carton will not collapse when bottles are taken out by the brewer for filling. Furthermore, substantial protection against breakage is afforded by the full length of the partitions with reference to the height of the carton walls.

Referring now to the modified arrangement disclosed in Figs. 11-21, the blank shown therein without closure flaps produces a twelve-cell carton when folded and assembled. Particularly referring to the modified blank of Fig. 11, it will be seen that the blank consists of two blanks precisely like the blank illustrated in Fig. 1 inso-

far as essential structural detail is concerned, these sections of the blank being designated A and B in Fig. 11. Sections A and B are joined to each other by a transverse score line 71 connecting side walls 72 and 74 of adjacent transverse portions of sections A and B which, as hitherto stated, correspond in every way insofar as essential functional features are concerned with the blank illustrated in Fig. 1.

The blank of Fig. 11 comprising sections A and B is folded along a vertical score line 76 to assume the position illustrated in Figs. 12 and 13 and is then folded about vertical fold lines 78 to assume the position illustrated in Figs. 14 and 15. The right-hand end of the blank is then folded over along vertical score line 80 to assume the position illustrated in Figs. 16 and 17.

The adhesively surfaced portions of the blank 32', 36' and 34' are precisely the same as has been described in conjunction with the blank of Fig. 1 and they cooperate with precisely the same sections or elements of their respective transverse sections as has been described in connection with the blank of Fig. 1. When the adhesively coated surfaces have been adhered and end pressure is placed upon the flattened carton of Fig. 17, the carton assumes the position illustrated in Figs. 18 and 19 and comprises three aligned tubular cells as illustrated in Figs. 18 and 19.

Section A so formed is swung back against section B along score line 71, which constitutes a hinge, in the direction indicated by the arrows in Fig. 19. Each of the two adjacent transverse rows of three cells of which sections A and B respectively are composed is then swung back along hinge lines indicated in Fig. 19 as 82 and 84, which hinge lines are formed by score lines in sections A and B conforming precisely to the hinge line formed by score lines 28 and 30 of the blank illustrated in Fig. 1. The carton then assumes the form illustrated in Figs. 20 and 21 wherein four rows of three cells are provided, the walls between each row of cells being of double thickness as indicated generally at 86.

Having described certain preferred embodiments of the invention, various modifications falling within the basic concept may be apparent to those skilled in the art, and for that reason I wish to limit myself only within the scope of the appended claims.

What I claim is:

1. A partitioned article carrier fabricated from a blank of flexible paperboard stock and including a pair of side wall panels, a bottom connected to the lower margins thereof, end wall panels hingedly connected to opposite end margins of each of said side wall panels, and partition-forming sections hingedly connected to the opposite end margins of each of said respective end wall panels, said sections being of unequal length, the longer partition sections being subdivided by parallel creases into a relatively wide, uncreased longitudinal partition-forming panel immediately adjoining each of the corresponding end wall panels at one end of the side wall panels and a plurality of cross partition-forming and side wall engaging panels of lesser width which are successively hinged to said last named longitudinal partition panel and to one another, the shorter partition sections constituting longitudinal partition-forming panels of lesser width than the first named longitudinal partition-forming panels which are, in the completed condition of the carrier, disposed in substantially coplanar relation with the first named longitudinal partition-forming panels, and the respective longitudinal partition-forming panels of said longer and shorter sections being in back-to-back relation to one another, said partition sections being substantially coextensive in height with said side wall panels, and the longitudinal partition-forming panels of said respective panel sections being integrally connected to one another by a crease coinciding with the top of the longitudinal partition.

2. In a partitioned article carrier fabricated from a blank of flexible paperboard stock and including a pair of side wall panels, end wall panels hingedly connected to opposite end margins of each of said side wall panels, partition-forming sections hingedly connected to the opposite end margins of each of said respective end wall panels, and means forming a bottom, one pair of said partition-forming sections being subdivided into first longitudinal partition-forming panels immediately adjoining each of the corresponding end wall panels at one end of the side wall panels and a plurality of cross partition-

forming and side wall engaging panels successively hinged to said last named longitudinal partition panel and to one another, the other pair of said partition-forming sections constituting second longitudinal partition-forming panels which are, in the completed condition of the carrier, disposed in substantially coplanar relation with said first longitudinal partition-forming panels, and the respective longitudinal partition-forming panels of said first and second sections being in back-to-back relation to one another, the longitudinal partition-forming panels of said respective panel sections being integrally connected to one another by a crease coinciding with the top of the longitudinal partition.

3. In a partitioned article carrier in accordance with claim 2 and wherein said longitudinal partition-forming panels have openings in the upper portions for providing hand holds.

4. In a partitioned article carrier in accordance with claim 3 and wherein said longitudinal partition-forming panels have upwardly extending integral flaps hinged at the upper border of said openings to facilitate the carrying operation.

5. In a partitioned article carrier fabricated from a blank of flexible paperboard stock and including a pair of side wall panels, end wall panels hingedly connected to opposite end margins of each of said side wall panels, partition-forming sections hingedly connected to the opposite end margins of each of said respective end wall panels, and means forming a bottom, one pair of said partition-forming sections being subdivided into first longitudinal partition-forming panels immediately adjoining each of the corresponding end wall panels at one end of the side wall panels and a plurality of cross partition-forming and side wall engaging panels successively hinged to said last named longitudinal partition panel and to one another, the other pair of said partition-forming sections constituting second longitudinal partition-forming panels which are, in the completed condition of the carrier, disposed in substantially coplanar relation with said first longitudinal partition-forming panels, and the respective longitudinal partition-forming panels of said first and second sections being in back-to-back relation to one another, the longitudinal partition-forming panels of said respective panel sections being integrally connected to one another by a crease coinciding with the top of the longitudinal partition, said first and said second longitudinal partition-forming sections overlapping each other through a portion of their

lengths to form a second crease adjacent said first mentioned crease and coinciding with the top of the longitudinal partition.

6. In a partitioned article carrier fabricated from a blank of flexible paperboard stock and including a pair of side wall panels, end wall panels hingedly connected to opposite end margins of each of said side wall panels, partition-forming sections hingedly connected to the opposite end margins of each of said respective end wall panels, and means forming a bottom, one pair of said partition-forming sections being subdivided into first longitudinal partition-forming panels immediately adjoining each of the corresponding end wall panels at one end of the side wall panels and at least two cross partition-forming panels and at least two side wall engaging panels successively hinged to said last named longitudinal partition panel and to one another to form at least six cells, the other pair of said partition-forming sections constituting second longitudinal partition-forming panels which are, in the completed condition of the carrier, disposed in substantially coplanar relation with said first longitudinal partition-forming panels, and the respective longitudinal partition-forming panels of said first and second sections being in back-to-back relation to one another, the longitudinal partition-forming panels of said respective panel sections being integrally connected to one another by a crease coinciding with the top of the longitudinal partition, said first and said second longitudinal partition-forming sections overlapping each other through a portion of their lengths to form a second crease adjacent said first mentioned crease and coinciding with the top of the longitudinal partition.
